UNITED STATES PATENT OFFICE.

WILLIAM E. WOODARD, OF FOREST HILLS, NEW YORK.

LOCOMOTIVE AUXILIARY CYLINDER-PORT ARRANGEMENT.

Application filed May 2, 1925. Serial No. 27,431.

This invention has particular reference to that type of locomotive which is known as a limited cut-off structure, these locomotives being generally operated with what is called a maximum cylinder cut-off of say 50 to 60%. In order that such limited cut-off locomotive may start freely at all positions of the crank, it has been heretofore proposed to apply what are known as starting ports which allow a small amount of steam to be admitted to the cylinders for starting purposes. These small starting ports are so disposed in the apparatus that they may be controlled by the valve which also controls the main ports. In connection with the operation or use of such starting ports certain difficulties have been countered in practice due to the fact that in regular locomotive service these ports tend to become clogged with carbon from the oil used and from this cause may become inoperative. In order to clean out such ports, it has been heretofore the practice to remove the steam chest heads and take out the steam chest valves which involved considerable delay and expense.

My present invention contemplates such a disposition of these starting ports in connection with the cylinder castings and such an arrangement of the cylinder casting itself that these ports may be reached from the outside without having to take off the steam chest heads.

In order that my invention may be better understood, I will proceed to describe the same in connection with the accompanying drawings in which

Fig. 1 shows a vertical section through a valve bushing with my improvement applied thereto;

Fig. 2 is a sectional view on a transverse plane, the section of Fig. 1 being taken on the line 1—1 of Fig. 2;

Fig. 3 is a transverse sectional view through a valve bushing and chamber showing a different location of the parts constituting my improvement;

Fig. 4 is a longitudinal sectional view on the line 4—4 of Fig. 3; and

Fig. 5 is a detailed sectional view taken on the line 5—5 of Fig. 4.

Referring now more particularly to Fig. 1 it will be seen that I have therein provided a starting port 1 on top of the steam chest valve bushing 2, the regular port opening 55 being shown at 3. Above this starting port 1, I provide a small chamber 4 formed in the casting and connected by an opening 5 with the chamber 6 which extends around the port 3. Above the chamber 4 I provide an opening in the casting which is closed by a removable screw threaded plug 7 which can be readily taken out when access is desired to the port 1 for cleaning purposes.

The chamber 4 arranged as shown within the wall of the casting 8 constitutes an oil reservoir into which oil can be readily poured after removal of the outside plug 7 and in which if the port is clogged a small quantity of the oil will lodge which can then be ignited and thus burn out the starting port providing a ready means of cleaning it from such materials as burned oil or similar obstructing substances. If necessary some tool such as a scraper or wire can be introduced directly through the opening which is normally closed by the plug 7 and which stands for this purpose directly opposite the starting port.

In Figs. 3 and 4 the starting port is located at the side of the valve bushing at the point marked 9 and the oil pocket 10 is made of a slightly different formation adapted to this location.

I claim:

1. A locomotive auxiliary cylinder port arrangement comprising in combination a valve bushing, a starting port therein, an opening in the cylinder steam chest opposite said port through which said port may be cleaned, means for closing said opening and an oil receiving pocket between the starting port and the cleaning opening.

2. In a locomotive steam chest, the combination of a valve bushing, a main steam port 95 in said bushing, a steam passage communicating with said main port, a comparatively small capacity auxiliary steam port in the

bushing, a pocket communicating with said auxiliary port, and an opening in the steam chest wall affording access to said auxiliary port through the pocket, said pocket communicating with said passage.

3. In a locomotive steam chest, the combination of a valve bushing, a main steam port in said bushing, a steam passage communicating with said main port, a comparatively small capacity auxiliary steam port in the bushing located well above the bottom por-

tion thereof, a pocket communicating with said auxiliary port, an opening in the steam chest wall opposite the auxiliary port affording access to said auxiliary port through said pocket, and removable means for closing said opening, said pocket communicating with said passage. 15

In testimony whereof, I have hereunto signed my name.

WILLIAM E. WOODARD.
